UNITED STATES PATENT OFFICE.

MARSHALL BURNS LLOYD, OF MENOMINEE, MICHIGAN, ASSIGNOR, BY MESNE ASSIGNMENTS, TO THE ELYRIA IRON & STEEL COMPANY, OF ELYRIA, OHIO, A CORPORATION OF OHIO.

TUBE-FORMING MACHINE.

1,178,812.

Specification of Letters Patent.

Patented Apr. 11, 1916.

Application filed May 19, 1913. Serial No. 768,539.

To all whom it may concern:

Be it known that I, MARSHALL B. LLOYD, a citizen of the United States, and a resident of Menominee, in the county of Menominee 5 and State of Michigan, have invented certain new and useful Improvements in Tube-Forming Machines, of which the following is a specification.

My invention relates generally to mechanism for forming tubing, and has particular reference to mechanism for forming tubing from strip metal stock.

The general object of my invention is to provide mechanism for making tubing from strip stock in such manner that the tube seam will remain closed after emerging from the forming mechanism.

Another object of my invention is to provide a mandrel for use in tube-forming machinery which shall act in conjunction therewith to set the tube edges permanently together and if desired without reducing the thickness of the metal; and a further object is to provide a mandrel for use in tube-forming mechanism which shall act with minimum frictional contact with the tube, to the end that the mechanism may be operated with minimum power; that the life of the mandrel may be increased; and that tubing may be made continuously with little attention.

My invention consists generally in the unique construction, arrangement, and co-operation of the parts whereby those objects named above, as well as others which will appear hereinafter, are attained.

My invention will be more readily understood by reference to the accompanying drawings, which illustrate the preferred form of my invention, and in which:

Figure 1 is a plan view of mechanism embodying my invention; Figs. 1^a, 1^b, 1^c, and 1^d are detail views illustrating the evolution from a strip metal to that of a completed tube; Fig. 2 is substantially a longitudinal vertical section on the line 2—2 of Fig. 1; Fig. 3 is a perspective view of the mandrel used in conjunction with the tube forming rolls; Fig. 4 is an enlarged side elevation of the head portion of the mandrel; Fig. 5 is a plan view thereof; Fig. 6 is a cross sectional view substantially on the line 6—6 of Fig. 4 showing the manner of housing the rolls; Fig. 7 is a fragmentary view in elevation of one-half of the mandrel

head showing the roll-receiving cavities; Fig. 8 is a view, similar to Fig. 7, but showing roll-receiving recesses of modified form; and Figs. 9 and 10 are respectively enlarged fragmentary views showing the operation 60 of the mandrel with the final forming rolls.

For many purposes it is desirable and necessary to provide tubing having the seam tightly closed. For example, when making tubing from strip stock to be welded it is 65 desirable to have the seam tightly closed in order that the welding flame will not "cut through" the seam and spoil the tubing. It is also desirable to have the ends of the tube, cross-sectionally considered, abut in 70 manner to form a smooth joint at the seam, i. e., to keep the ends from overlapping or projecting above or below the adjacent end. These desired features, however, should not be attained at the expense of greatly 75 reducing the thickness of the metal or of requiring tremendous power and much labor.

I shall now describe in detail my unique mechanism whereby tubing, with tightly 80 closed seams, can be manufactured from strip stock with minimum amount of labor, substantially without reducing the thickness of the metal, and with smooth abutting ends and at low cost.

The mechanism is mounted upon a strong table or bench Z and comprises generally the initial forming mechanism A and the final forming mechanism B. The initial forming mechanism A may be of any of 90 the well-known constructions and may comprise one or more sets of forming rolls or dies. I find, however, that one set of forming rolls serves well to give the strip its first form. These comprise upper and lower rolls a^1 and a^2 which are slidably mounted in standards a^3 . The rolls are vertically adjustable by means of adjusting screws a^4 . This tube-forming mechanism is well adapted for and is much used in the continuously 100 making of tubing from strip stock and is particularly adapted for forming the metal into tubes in condition for welding. The strip metal C is usually fed from a large reel (not shown) and enters the initial forming mechanism A through a guide G. The guide G is adjustable to accommodate various widths of strip stock and of course by providing different sized forming mechanisms, tubes of various diameters can be

made. The strip stock is shown in Fig. 1^a as it enters the first forming mechanism and in passing therethrough assumes the shape indicated in Fig. 1^b. The strip enters the final forming mechanism B and emerges therefrom in the form of a tube having a seam which is tightly closed. After its emergence from the final forming mechanism B, I often perform one or more operations upon it, but they are in no wise essential to the present invention. I usually provide some sort of draft mechanism such, for instance, as the continuous vise E, shown in my Patent No. 1,027,865 of May 28, 1912. 10 I have not shown the draft mechanism here inasmuch as any suitable draft mechanism will suffice, or in lieu of a separate mechanism to draw the strip through the forming mechanism, A and B, I may drive either or 15 both sets of rolls constituting the forming mechanism. I prefer, however, to drive the initial forming rolls A and to depend upon the same to force the strip through the final forming mechanism B either independently or 20 in conjunction with a separate draft mechanism such as before mentioned. For purposes of driving the rolls a^1 and a^2 , I provide the upper and the lower shafts a^5 and a^6 respectively with intermeshing gears 25 and a^7 and drive one of the shafts from any suitable source of power by means of the belt and pulley a^8 .

The final forming mechanism here shown comprises a plurality of pairs of horizontally arranged forming rolls b^1 , b^2 , and b^3 , mounted in a frame B^1 rising from and secured to the table Z. The rolls are mounted in journal boxes b , which are slidably held in the frame B^1 , being adjustable by means 35 of screws b^4 . The rolls b^1 , b^2 , and b^3 , are provided with different shaped grooves b^6 , b^7 , and b^8 , and they serve gradually to form the strip metal from the shape indicated in Fig. 1^b of the drawings to that of a substantially finished tube, as indicated in Fig. 1^c. The last set of rolls b^8 and b^9 are preferably mounted for rotation in vertical planes and are held in vertically adjustable boxes b^{10} slidably arranged in the stand- 40 ard portion, B^3 , of the frame and are adjustable by means of screws b^{11} , and b^{12} . They contain grooves b^{13} and b^{14} , the shape of which is dependent upon the desired form of tube. In this instance I desire to make 45 a circular tube and have therefore made the grooves substantially semi-circular in shape. The rolls b^8 and b^9 would in and of themselves serve to shape the strip metal as it is forced therethrough to substantially the 50 shape of the combined recess, but so soon as the tubing would emerge from the rolls b^8 and b^9 the resiliency of the metal would cause the seam to open. As before stated, it is one of the objects of my invention to 55 provide mechanism for making tubing with

the butt seams tightly closed. I therefore provide mechanism coöperable with the forming rolls b^8 and b^9 to give the tubing a permanent set as it passes therethrough. This mechanism consists of a mandrel D of 70 unique construction, which comprises a head portion d^1 and a shank portion or tension rod d^2 . Secured to one end of the shank portion d^2 is an upstanding member d^3 which is secured to a block d^4 carried by the 75 frame B^1 . The mandrel, as shown in Fig. 2, extends from a point adjacent the initial forming rolls A, where the strip is only partially formed, into the tube and forward of the rolls b^8 and b^9 . In order that I may 80 accurately adjust the position of the head d^1 , which coöperates with the forming rolls b^8 and b^9 , I secure the block d^4 , carrying the mandrel, adjustably to the frame B^1 by means of the elongated slots d^5 and the stay 85 bolts d^6 arranged therein. Although the mandrel head may be placed to coöperate with the rolls slightly on either side of or in the center of the rolls, I prefer to place it so that the coöperating portion will be 90 slightly forward of the center of the rolls.

In the continuous formation of tubing with the ordinary form of mandrel, considerable friction is produced by engagement of the mandrel with the inner surface 95 of the tubing and this is augmented when it is attempted to force the ends of the tubing, cross-sectionally considered, together in order to close the seam permanently. This excessive friction causes the mandrel to 100 gather dirt and foreign matter from the metal and also causes it to scrape off a portion of the inner surface of the tube, thereby reducing in a measure the thickness of the metal. The mandrels now in general 105 use, when subjected to such treatment, require frequent cleaning and also soon wear out. These conditions make it extremely difficult to produce tubing continuously from strip stock, in which the seam is tightly 110 closed, which is of uniform size and which is not materially reduced in thickness by its passage through the forming mechanism. These objectionable features are overcome 115 by my unique mandrel. I provide the head portion d^1 of the mandrel with rolls d^{14} and d^{15} which roll one upon the other and which together are slightly greater than the thickness of the head portion. These rolls engage the inner surface of the tubing and serve to 120 distort it in manner to close the seam. The action of the rolls d^{14} and d^{15} will be best understood by reference to Figs. 2, 9, and 10. Fig. 9 is an enlarged detail sectional view of the tubing slightly to the left of the center 125 of the rolls. The tube T, as there indicated, conforms substantially to the grooves b^{13} and b^{14} , respectively, of the upper and lower rolls. The curvature of the recess b^{14} in the lower roll, however, is slightly more 130

acute than that of the upper roll and of the tubing, thereby forming a small space b^{15} between the lower side of the tubing and the upper portion of the lower forming roll. 5 The seam t , as defined by the end portions t^1 , t^2 of the tube, is substantially closed, but, as before stated, if the tube were not treated further, upon emerging from the rolls b^8 and b^9 , the portions t^1 and t^2 would spring 10 away, thereby opening the seam. I overcome this by forcing the portion t^3 of the tube downwardly, as indicated at b^{16} , to close the space b^{15} , thereby throwing the portions t^1 , t^2 of the tube tightly together. This 15 action is best shown in Figs. 2 and 10 of the drawings, where it will be seen that the upper and lower rolls d^8 and d^9 , acting together, firmly press the metal into conformity with the grooves of the upper and lower 20 rolls. For the sake of convenience, I shall term this operation "distorting the tube to close the seam". Now when the tube emerges from the forming rolls, the seam will remain tightly closed, as indicated in 25 Fig. 1^a. I have considerably exaggerated the deforming effect of the mandrel upon the tube in Fig. 1^a in order that the idea may be readily understood.

Another advantage to be derived from the 30 use of my mechanism, is that the pressure of the rolls against the tubing, as indicated in Fig. 10, serves to bring the end portions of the tube t^1 and t^2 exactly into line, that is, form them so that they match and do not 35 overlap, nor do they extend above or below each other. This is a valuable feature, inasmuch as it provides a tube of neat appearance and increased strength, but is particularly valuable when the tubing is to be welded, since the flame playing upon the 40 portions of the tube adjacent the seam will heat them uniformly and when the pressure is applied a weld of greater strength is attained. The tube also is in better shape for 45 finishing, if the same is desired, than it would be if the joint were not smooth.

By properly shaping and proportioning the upper and lower rolls of the mandrel I 50 can slightly decrease the thickness of the tube just at the bottom enough to force the metal into the side portions of the tube (cross sectionally considered) and thereby close the seam. Ordinarily, however, I prefer not to reduce the thickness of the tube at 55 any place but to close the seam as before described by slightly distorting the tube.

The head portion of the mandrel comprises two substantially semi-cylindrical portions d^{16} and d^{17} which are secured together by binding screws d^{18} . The shank or tension portion d^2 of the mandrel is secured 60 to the head portion by the screws d^{19} . I provide recesses d^{20} in the portions d^{16} and d^{17} to which the rolls substantially conform and 65 in which they are rotatably held. The head

is cut away, as indicated at d^{21} and d^{22} , to expose the portions of the upper and lower rolls. In order that the rolls may be easily lubricated, I provide a groove d^{23} in the upper portion of the mandrel shank which 70 communicates with a groove d^{24} of the mandrel head and by inclining this groove slightly to the rolls, they may be readily lubricated. It is obvious that the frictional engagement between the mandrel and the 75 tubing is greatly minimized by the provision of these rolls, and, as before stated, that the rolls serve the further function of distorting the tube for the purpose of giving it a permanent set. My unique mandrel may 80 be used continuously for a great length of time and will enable the production of uniformly sized tubing. Further, when necessary, the working parts can be easily repaired and cleaned. 85

I have shown a modified form of mandrel in Fig. 8. In this case, instead of making the recesses in the mandrel head to conform substantially to the rolls, they are formed to provide only lines of contact with the 90 rolls. I accomplish this by forming recesses having flat defining walls d^{25} so that the rolls, as indicated in dotted lines, engage the same only along the center lines of the sides. In this manner the frictional contact 95 of the rolls with the head is decreased.

The mechanism herein shown and described serves admirably to accomplish the objects sought for, but since this disclosure will suggest to others skilled in the art, 100 modified structures adapted to accomplish substantially the same objects, I do not wish to limit my invention to the specific construction and arrangement herein shown and described. 105

I claim:

1. A mandrel for tube-forming machines comprising a tension rod portion and a head portion, said head portion consisting of two substantially semi-cylindrical parts, two 110 contiguous recesses in each said semi-cylindrical part of the head portions, means for assembling the two semi-cylindrical portions with the recesses thereof aligned, anti-friction rollers arranged in said recesses, the head portion being cut away to expose a portion of each roll, and a groove leading from the tension rod portion to the anti-friction rolls. 115

2. In a tube forming machine, a plurality 120 of pairs of dies, for bending strip material of substantially circular form in combination with a mandrel positioned to coact with one pair of dies, opposed rolls in said mandrel, the said co-acting dies having a section 125 which differs from the semi-circular section of the tubing by being somewhat more curved, thus forming a space to permit deformation of the tube by the said rolls. 130

3. The herein described improved means for converting an outwardly resilient and hence open butt-seamed tube into an inwardly resilient and hence tightly closed butt-seamed tube, comprising an external die composed of opposed rolls presenting a die opening substantially conforming to the cross section of the outwardly resilient tube, in combination with a mandrel of greater effective diameter than the outwardly resilient tube but of less width, said mandrel being positioned within said die and tube and acting to hold the seam edges of the tube and distorting the tube opposite said seam edges.
4. The herein described improved means for converting an outwardly resilient and hence open butt-seamed tube into an inwardly resilient and hence tightly closed butt-seamed tube, comprising an external

die composed of opposed rolls presenting a die opening substantially conforming to the cross section of the outwardly resilient tube, in combination with a mandrel of greater effective diameter than the outwardly resilient tube but of less width, the greatest diameter of said mandrel being marked by anti-friction rolls and said mandrel being positioned within said die and tube and the anti-friction rolls thereof acting to hold the seam edges of the tube while distorting the tube opposite the seam. 25

In testimony whereof, I have hereunto set my hand this 8th day of May, 1913, in the presence of two subscribing witnesses.

MARSHALL BURNS LLOYD.
